Patented Feb. 13, 1962

192,208

SHOE HEEL PROTECTOR

Ira Bradley and Branch B. Ray, both of 3710 Ruthelen
St., Los Angeles, Calif.

Filed Aug. 7, 1961, Ser. No. 66,228

Term of patent 14 years

(Cl. D7—5)

We claim:

The ornamental design for a shoe heel protector, substantially as shown.
